POWER BENDER

William J. Hall, Detroit, Mich., assignor to
 Herron-Zimmers Moulding Company, Detroit,
 Mich., a corporation of Illinois

Application November 3, 1939, Serial No. 302,632

19 Claims. (Cl. 153—40)

The invention relates generally to metal bending machines, and it has particular relation to a machine for bending a window frame member into annular form frame.

In general, the use of power benders for the purpose described above is not new, and many machines have been advanced for accomplishing the results stated. In a machine of this general type, certain factors should be considered, and it is because of these factors that many machines heretofore advanced are inefficient. For one thing, it is important that the metal frame member be bent into annular shape, in a rapid manner, and that insertion of the strip and removal of the formed frame be accomplished easily and rapidly to the end that the cost of bending of the strips may be reduced as much as possible. Again it is important that the strip have a smooth surface at the bends, and in many instances with machines heretofore designed, it has been difficult to obtain a smooth surface in the region of sharp bends, at least economically.

Also, it is important that the machine be not too expensive to manufacture, and that its cost of maintenance be not too large. In the past, one objection to many of the machines designed has been that the initial cost is too large and that, due to complicated arrangements, shutdowns have been prolonged when one part of the machine failed to function. When it is considered that enormous numbers of window frames are manufactured for use on automobiles, the importance that is attached to power benders may well be appreciated.

One object of the present invention is to provide an improved power bender which will enable obtaining greater rapidity in bending operations while still obtaining a finished product free from undesirable wrinkling or deformation.

Another object of the invention is to provide a power bender for accomplishing the results mentioned in the preceding object, which is inexpensive to construct and which is of simple character to the end that the cost of initial installation, the cost of repair, and delays incident to repairs will be reduced to a minimum.

Another object of the invention is to provide an improved power bender which is particularly adapted to effect the bending of metal strips of irregular contour, in the region of sharp bends, and to accomplish this sharp bending rapidly and smoothly.

Other objects of the invention will become apparent from the following specification, from

the drawings relating thereto, and from the claims hereinafter set forth.

For a better understanding of the invention, reference may be had to the drawings wherein:

Figure 1 is a plan view of a power bender constructed according to one form of the invention;

Fig. 2 is a side elevational view of the machine shown by Fig. 1;

Fig. 3 is a cross-sectional view taken substantially along the line 3—3 of Fig. 2;

Fig. 4 is a cross-sectional view on a larger scale, taken substantially along the line 4—4 of Figure 1;

Fig. 5 is a cross-sectional view taken substantially along the line 5—5 of Fig. 4;

Fig. 6 is a cross-sectional view taken substantially along the line 6—6 of Fig. 4;

Fig. 7 is a cross-sectional view on a larger scale, taken substantially along the line 7—7 of Fig. 1;

Fig. 8 is a cross-sectional view taken substantially along the line 8—8 of Fig. 7;

Fig. 9 is a cross-sectional view on a larger scale taken substantially along the line 9—9 of Fig. 4;

Fig. 10 is a cross-sectional view taken substantially along the line 10—10 of Fig. 6;

Fig. 11 is a diagrammatic illustration showing an electric circuit which may be employed for controlling operation of the power bender;

Fig. 12 is a detailed view illustrating one of the window frames which has been formed from a straight strip by means of a power bender such as illustrated; and

Fig. 13 is a cross-sectional view on a larger scale, taken substantially along the line 13—13 of Fig. 12.

Referring to Figs. 1, 2 and 3, the bender illustrated includes a top 10, uprights 11 supporting the top, and a base 12 upon which the uprights are supported. Now directing attention particularly to Figs. 2 and 3, an electric motor 13 is mounted on the base 12 and is drivingly connected to a variable speed transmission 14 which has a pinion 15 in turn connected by means of a link belt 16 to a pinion 17 mounted on a shaft 18. The pinion 17 is loose on the shaft 18 excepting that it is positioned axially by means of a collar 19 on the shaft, and opposite to the collar, the pinion is connected to a female clutch element 21. A male clutch element 22 splined to the shaft and connected by means of linkage 23 to a clutch actuating member 24 is adapted to drivingly connect the pinion 17 to the shaft.

Movement of the member 24 axially of the shaft

may be accomplished by means of a conventional clutch engaging collar 26 and a bifurcated pivotal lever 27, and it will be readily understood by those skilled in the art how such parts are constructed in detail.

The lever 27 is pivoted at a point indicated at 28 and is adapted to be moved about its pivot by means of a link 29 pivotally connected to a solenoid 32 which in turn is connected to a solenoid 31 by a pin 33. In this connection, it may be explained that when the solenoid 32 is energized, the clutch actuating member 24 is moved so as to cause the male and female clutch members to engage and when the solenoid 31 is energized, the clutch members are caused to be disengaged, it being understood that only one of the solenoids is energized at a time.

The shaft 18 has another pinion 35 thereon that is keyed thereto and a solenoid brake 36 is provided at the end of the shaft opposite the clutch for stopping the shaft when the clutch is disengaged. A link belt 37 connects pinion 35 to a pinion 38 on an upper shaft 39 and as best shown by Fig. 2, the shaft 39 has a worm portion 40 which meshes with a worm wheel 41. The worm wheel in turn is keyed to the lower end of a vertical shaft 43 which projects upwardly through an opening in the top 10. It should now be understood that with the motor 13 constantly rotating, the shaft 43 may alternately be driven or be at rest depending upon actuation of the clutch operating solenoids. It may be mentioned that the driven parts described so far are enclosed within the base by means of a cover 45 which may have suitable openings or doors for allowing access to the parts.

As shown best by Fig. 4 the upper end of the shaft 43 turns in a sleeve bearing 59 located in the opening in the table 10, and above the bearing, the shaft has an enlarged portion 51 to which a plate 52 is secured by means of screws 53. A form block 54 in the form of an annulus substantially of the shape of the frame to be manufactured is rigidly secured to the plate 52 in any suitable manner, such as by screws, so that the form block and plate rotate together about the axis of the vertical shaft 43. At its outer side, the form block 54 as shown by Figs. 4 and 10, has an outwardly projecting flange 56 and this flange in conjunction with the upper surface of the form block and the vertical edge face above the flange, provides a seat of step formation adapted to receive a strip to be bent which is indicated at 57. With the understanding now that the form block 54 is rotated and that it has a stepped form for seating the strip 57, it will be seen that if the strip is maintained against the form block during rotation of the latter, the strip will be bent around the form block and will finally assume the shape shown by Fig. 12. Mechanism for locking the strip to the form block at one point and for properly maintaining the strip against the form block during rotation of the latter will now be described.

Now referring to Figs. 1, 4, and 6, it will be observed that the plate 52 at its underside and around its margin has an annular channel-way 60 and this channel-way receives rollers 61 and 62 which are turnably mounted on a pivotal member 63. The member 63 is pivotally mounted on an enlarged portion 64 of a vertical stub shaft 65 fixed in an opening 66 of a slide 67. A suitable bearing washer 68 and sleeve 69 are provided and a washer 70 disposed in a countersunk recess in the member 63 is secured by screws 75

71 to the upper end of the shaft 65 for anchoring the pivotal member 63 against vertical displacement upwardly from the slide. Now observing the peripheral contour of the channel-way 60, and also observing that the rollers 61 and 62 on the pivotal member 63 are disposed in alignment with the stub shaft 65 but at opposite sides thereof, it will be appreciated that when the plate 52 rotates, the pivotal member 63 can swing about the axis of the stub shaft 65 so as to accommodate its position to the curvature of the channel-way.

The slide 67 is guided between opposed guideways 75 and 76 secured by screws 77 to the top 10, and is adapted to move inwardly and outwardly depending upon inward and outward movement of the rollers 61 and 62 with respect to the axis of the shaft 43 during rotation of the plate 52. It has been mentioned that the pivotal member 63 turns about the axis of the stub shaft 65 depending upon the peripheral contour of the channel-way 60 and in this connection attention is directed to the fact that a curved bearing plate 80 is provided on the slide 67 and this bearing plate has supporting engagement with conical rollers 81 and 82 on the pivotal member 63. The bearing plate 80 is so positioned and the conical rollers 81 and 82 are so shaped and positioned that as the pivotal member 63 swings about the axis of the stub shaft 65, the rollers 81 and 82 have a free rolling contact with the bearing plate 80 as distinguished particularly from a rolling contact such as would occur if the rollers were cylindrical.

From the description so far set forth, it will now be apparent that as the plate 52 rotates, the rollers 61 and 62 will be displaced inwardly and outwardly along the pathway of the slide 67 depending upon the change in shape of the channel-way 60 and at the same time such rollers will swing back and forth about the axis of the stub shaft 65 depending upon changes in direction of such channel-way. Such swinging of the rollers about the axis of the stub shaft 65 will cause the pivotal member 63 to swing about the axis of the shaft 65 and hence during rotation of the plate 52 the pivotal member 63 will swing about the axis of the shaft 65 and simultaneously may move inwardly and outwardly with the slide 67. It might be mentioned at this time that the pivotal member 63 carries a wiper block for holding and pressing the frame member 57 against the form block 54 and from this it may be initially appreciated that due to the pivotal and inward and outward movement of the member 63, the wiper block may rapidly change its position in accordance with the contour of the form block.

Now referring to Figs. 4 and 5, it will be observed that the pivotal member 63 carries what may be termed a box-like member 85 which is open towards the form block 54 and which has an end wall 86 closing its opposite end. In the lower part of this box-like member, a block 87 is provided which at its center has an upwardly open recess 88 slidably receiving a nut 89 substantially fitting the recess so that the nut cannot turn. This nut is threaded on an intermediate threaded portion 90 of a pin 91 which passes longitudinally through the block 87 and externally through the end wall 86. Collars 92 and 93 secured on the pin at the outer side of the end wall and at the inner end of the block 87, lock the pin against axial movement and also lock the block in position against the end wall 86. The

outer end of the pin 91 has a polygonal head 95 by means of which it may be turned, and it follows that when the pin 91 is turned, the nut 89 is moved longitudinally of the recess 88 in one direction or the other depending upon the direction of turning.

Above the block 87 a slide 96 is provided within the box-like member 85, and this slide has a recess 97 for receiving compression springs 98 and 99. That end of the recess 97 next to the end wall 85 is open and the ends of the springs at this end of the recess engage over pin-like elements 100 having collars 101 abutting the ends of the springs. The position of each pin element 100 is determined by means of a set screw 102 threaded through the end wall 86 and extending into an opening 103 in the collar 101 and pin element and which has a lock nut 104 outside the end wall. In this manner the loading of the springs may be adjusted depending upon the pressure desired.

At its left end, each spring engages over a pin 107 provided on an end wall 108 at the other end of the recess 97 and thus the slide 96 is urged towards the form block 54. For limiting the inner position of the slide 96, pins 110 and 111 shown best by Fig. 5 project downwardly from the lower wall of the slide and into the recess 88 of the block 87 and straddle the screw portion 90 at the outer side of the nut 89. It will now be apparent that by adjusting the position of the nut 89, the limiting position of the slide 96 may be governed since movement of the nut 89 will through engagement of the nut with the pins 110 and 111 effect or allow movement of the slide accordingly.

At the forward end of the slide 96, upper and lower arms 112 and 113 are provided and between these arms a bearing bracket 114 is pivotally arranged by means of a pin 115 passing vertically through apertures in the arms and in the bracket. The bearing bracket as shown best by Fig. 9, has a flange or plate portion 116 and at the front side of this plate, a wiper support 117 is provided and such a support is secured to the plate 116 by means of screws 120. Such support 119 has spaced projections 121 and 122 terminating at their forward ends in vertically disposed cylindrical portions and a pivotal member 123 has a restricted opening receiving the cylindrical projection 121 while a similar member 124 receives the cylindrical projection 122. The members 123 and 124 slidably rest on the plate 52 and while movable vertically on pivots 122 and 121, it will be observed that in operative positions, the members have lower flange portions 125 which project under the flange 56 of the form block 54 and thus upward movement is definitely limited. Pivotal movement of the members 123 and 124 about pivots 121 and 122 is limited as is evident in Fig. 9.

As shown particularly by Fig. 4, the member 123 has vertically spaced, but upwardly inclined surfaces 127 and 128 and such inclined surfaces are adapted to fit and guide a movable wiper block 130. Such block is maintained movably assembled with the member 123 by means of screws 135 threaded downwardly through the member at right angles to the inclined surface 127 and on opposite sides of pivot 121 and which have their lower ends slidably positioned in slots 136 in the block. Also inclined screws 137 are provided on opposite sides of pivot 121 and each screw is threaded through a wall 138 of the bearing bracket and has its free end projecting

5 into an opening 139 in the block. Between the block and wall 138, a spring 140 is provided around each screw from which it follows that normally the springs urge the block along the inclined surfaces 127 and 128.

The screws 137 and 135 are located at right angles to each other and this arrangement in conjunction with the inclined surfaces mentioned before, holds the block assembled with the member 123, while it still permits limited movement of the block along the inclined surfaces.

The member 124 similarly supports a block 143 shown by Fig. 9. The blocks 130 and 143 are arranged similarly to the members 123 and 124 so that each block and its supporting member may rock with respect to the other block and its supporting member within limits. An arm 145, having a rounded edge 147, is fastened to the upper side of the bearing bracket 117 by means of screws 146 as shown by Fig. 9, and this arm is adapted to automatically release the strip clamping means that will be described presently.

Referring to Figures 9 and 10 in particular, the block 130 has an extension 150 adapted to contact the lower angular portion only of the strip 57 so as to effect or obtain wiping action over a greater linear portion of the vertical web and the lower flange of the strip. The block 123 has an extension 151 projecting longitudinally under the flange 56 of the form block 54 and this extension has spaced openings 152 and 153 which constitute guideways for pins 154 and 155 projecting from a bar 156. This bar at its side next to the form block 54 has a flange 158 seen as contacting the edge face of the flange 56 of the form block while at the opposite side of the bar 156, a pin 160 extends through an offset portion 161 of a bracket 162 secured by screws 163 to the extension 151. A spring 165 around the pin 160 between the bar 156 and the offset 161 constantly urges the bar and the flange portion 158 towards the flange 56 on the form block. Preferably the wiper blocks 130 and 123 will be constructed from a softer metal such as brass in order to prevent scratching

45 of the frame member 57.

For holding one end of the strip 57 in locked relation to the form block, a locking arrangement is provided which is particularly shown by Figures 7 and 8. As shown by Figure 8, the form block is notched out as indicated at 170 and within the notch a pivotal locking element 171 is provided which is pivoted on a screw element 172 threaded into the form block. A lip 173 is provided on the element 171 and adapted to clamp the vertical flange portion of the strip 57 against the vertical face of the form block 54. For turning the clamping element 171 about the pivot 172, a pin 175 is provided which has an eccentric pin portion 176 disposed in an elongated opening 177 in the element and when the pin 175 is turned, the clamping member 171 is turned about the pin 172. At its upper end, the pin 175 extends through a bearing plate 180 fastened to the form block and a long handle 181 is secured to the pin to facilitate turning thereof. A limit stop pin 182 projects upwardly from the bearing plate 180 so as to limit clockwise turning movement of the arm 181 to a clamping position. A short arm 183 is also fastened to the pin 175 and, with reference to Fig. 1, when the arm 181 is turned clockwise until it engages the limit pin 182 so as to effect clamping of the end of the strip 57, the short arm will be turned to a position where it will strike 50 the arm 145 on the wiper block device when the

bending operation is completed. This automatically effects unclamping of the strip.

Now directing attention to Figs. 1 and 4, it is to be observed first in Fig. 1 that the channel-way 60 along the longer side adjacent the strip clamping means, continues in a straight line or direction, whereas the form block diverges inwardly to the clamping means and then outwardly from the clamping means. It will be understood that the limit nut 89 in Fig. 4 may be so set as to allow the main springs 98 and 99 to hold the wiper blocks strongly against the strip during the bending operation, while at the same time the setting of the nut in conjunction with the divergence of the channel-way 60 and form block may be such as to cause the wiper blocks to be pulled away from the strip or form block. Thus with the parts positioned as in Figs. 1 and 4, the wiper blocks are away from the form block and this allows easy initial linear insertion of a new strip as well as removal of the finished frame. The adjustment of nut 89 in conjunction with the divergence of the channel-way 60 and form block also will be such as to allow the wiper blocks to pass over the locked clamping means without interference. In this connection it will be understood that if the wiper blocks are moved away from the form block and strip completely, the wiper blocks may be urged upwardly along the inclined surfaces 127 and 128 but are prevented from separating from such surfaces by the guiding screws or pins 135 and 137. However, when the wiper blocks are moved inwardly against the vertical web part of a new strip 57, such blocks and the supports 123 and 124 have relative movement along the inclined surfaces 127 and 128 until the blocks forcefully contact the horizontal and vertical parts of the strip and the flange portions 125 of the supports forcefully contact the under side of the flange 56 of the form block 54. Thus the strip is tightly clamped both in a vertical direction and in an horizontal direction, although the clamping action will be of such nature as to allow the parts to have sliding contact during operation of the machine.

With reference to Fig. 11, the main lines of an electric circuit are indicated by the numerals 184 and 185 and it will be observed that two circuits 186 and 187 adapted selectively to be energized are employed. A two-way switch 188 is adapted to open one circuit and close the other and vice versa, and this switch is normally held by spring 189 in such position that the circuit 187 is energized. This circuit 187 includes the solenoid 31 for throwing the clutch out and also includes the brake solenoid 36 which actuates the brake mechanism for quickly stopping the shaft 18 when the clutch is thrown out. A switch 192 normally held in a closed position by a spring 193 is in the circuit 186 and this switch is adapted to be opened as shown by Figure 1, by a cam 194 on shaft 18 which is engageable with a roller 195 on the end of a movable bar 196 pivotally connected to the switch 192. Normally, the spring 193 within the switch box urges the bar 196 toward the center of the machine and the switch into closed position and it is only when the cam 194 moves over the roller 195 that the switch is opened. It is to be understood that as soon as the cam passes the roller 195, the switch returns to closed position.

A manually operated switch 198 located at a convenient place as seen in Figure 1, is adapted to initiate operation of the machine and this starting switch closes an auxiliary circuit 200, including a coil 201 which throws the switch 188

into position where it closes the circuit 186. As soon as the switch 188 closes the circuit 186, it also energizes a holding circuit 203, including a coil 204, which holds the switch in the position wherein it closes the circuit 186. Manual release of the starting button will then have no effect since the holding coil 204 maintains the circuit 186 closed. When the circuit 186 is closed, the solenoid 32 is energized, and simultaneously the solenoid 31 and the brake solenoid 36 are de-energized and accordingly, the clutch parts are engaged, the brake is released, and the machine starts operating. It will be understood that the cam 194 is barely past the roller 195 at the beginning of the operation and it follows that the circuit 186 will be maintained in a closed condition until the cam again reaches the roller 195 and then the switch 192 will be opened temporarily while the cam passes the roller. Opening of the switch 192 de-energizes the coils 32 and 204 and then the spring 189 returns the switch 188 to its other position wherein the clutch throw-out solenoid 31 and the brake solenoid 36 are energized. This stops the machine quickly, but it will be understood that the momentum is such and there is enough delay in the action to permit the cam 194 to move past roller 195 sufficiently to allow the switch 192 to return to its closed position. It follows that the parts are again set for manual starting by pushing of the button 198.

Assuming that the parts are in positions as seen in Figure 1, a new strip 57 is linearly inserted past the wiper means until the end of the strip is under the clamping lip 173. Then the handle 181 is turned clockwise until it engages the pin 182 and this operation tightly clamps the end of the strip to the form block. The manual switch 198 is then actuated to initiate operation of the machine, and this effects rotation of the plate 52 and the form block 54. As the plate rotates in a clockwise direction, the slide 67 and all of the parts carried thereby move outwardly in the guideways 75 and 76 owing to the fact that the rollers 61 and 62 follow the channel-way 60 and that part of the latter over the slide becomes more distant to the rotational axis as the plate turns. At the same time, the space between those parts of the form block and channel-way over the slide becomes less as the plate turns until the first bend in the form block and channel-way reaches the slide. As the channel-way and form block converge in their movement over the slide 67, the slide and wiper parts carried thereby necessarily become positioned nearer to the form block and the arrangement is such that the wiper blocks will contact the metal strip 57 at a point adjacent to the first bend in the form block.

With particular reference to Figure 4, it will be observed that before this contact of the strip with the wiper blocks occurs, the latter are in higher positions on the inclined surfaces of the wiper block supports but when the wiper blocks contact the vertical flange portion of the strip 57, the wiper blocks and wiper block supports have relative movements along the inclined surfaces thereon until the wiper blocks are drawn downwardly into tight frictional engagement with the horizontal surfaces of the strip 57 and the flange portions 125 of the wiper block supports are drawn upwardly into similar fitting engagement with the under side of the flange 56 of the form block. The form block, in pushing outwardly against the wiper blocks, first effects this clamping engagement of the blocks with the

metal strip and then upon sufficient outward movement of the form block relative to the outward movement of the slide 67, the outward movement of the form block will finally cause the slide 96 to move sufficiently to separate the limiting pins 110 and 111 from the adjustable nut 89. It follows from this that near the beginning of the first bend in the form block, the springs 98 and 99 come into action to exert strong resilient pressure against the wiper blocks and the metal strip 57.

As the first bend in the form block passes over the slide 67, the roller 62 on the pivotal member 63 is taking the first turn in the channel-way 60 and this effects swinging of the pivotal member about the axis of the stub shaft 65, and it thus follows that the pivotal member will roll over the bearing element 80. Now due to the pivot 115 carrying the wiper block parts on the end of the slide 96, and due to the fact that the slide 96 can move, the wiper blocks will tend to lag behind the movement of the pivotal member 63 in its swinging movement, so that the wiper blocks will tend to maintain resilient ironing pressure on the metal strip 57 in lagging relation to the movement of the pivotal member 63. This is important as the strip will be ironed, so to speak, by a lagging movement of the wiper blocks around the bend.

During the movement of the parts as so far described, and also during succeeding movements, it is desirable that the metal strip 57 be maintained against twisting as it approaches the form block and prevention of this twisting is effected by the member 158, shown by Fig. 10 particularly. This member 158 provides a support for the strip 57 and guides it properly into position between the form block and wiper blocks and especially when the strip is being bent around the bends of the form block, this is important, as twisting is apt to occur unless the strip is substantially supported. It should be stated in this connection, that as the wiper blocks begin to move around the bend in the form block, the wiper block 130 and its support 123 cannot maintain full surface contact with the form block as line contacts necessarily are involved, one on each wiper block. Since these line contacts will be approximately in the region of the pivotal projections 121 and 122, as seen in Fig. 9, it will be evident that at the advancing side of the block 130, the metal strip will not be held against the form block and will diverge therefrom. The projection 158 provides a support for the strip where it diverges from the form block and the spring mounting of this member tends to eliminate any gap between it and the form block flange, whereby continuity in the supporting surface for the diverging part of the strip may be maintained.

By providing both of the form blocks 130 and 143, and having them pivot relative to each other, it has been found that the tendency of wrinkles is even further decreased since the first form block will provide and advance wiper action and the second or lagging wiper block will iron out any wrinkles that possibly might have been left in the strip after the first wiper block has effected the bending action over the metal.

Bending of the strip about the remainder of the form block is effected in a similar manner, and it will be appreciated that as the bending operation is continued, the slide 67 will move inwardly and outwardly and the pivotal member 63 will swing in one direction and the other, depend-

ing upon the bending that is taking place. The arrangement is of such character that, relatively speaking, the pivotal member 63 swings rapidly around each bend and the metal strip is ironed around such bend in a rapid manner without wrinkling or twisting.

After the final bend in the form block passes the wiper mechanism, the channelways 60 and form block again diverge until finally the limit pins 110 and 111 again strike the nut 89, as seen in Fig. 4, and following this the wiper blocks move upwardly along the inclined surfaces mentioned, and finally assume the positions initially described, wherein they are substantially separated from the form block to permit easy removal of the finished frame and insertion of a new strip to be bent. During final movement of the plate 52 and form block, the arm 145 strikes the arm 183 on the clamping means and the latter is automatically turned backwardly by this action so as to release the metal strip. Then the cam 192 moves the rod 196 outwardly so as to open the switch 182 temporarily and from the previous description set forth, it will be appreciated that operation of the mechanism will now cease with the parts again in positions as shown by Figure 1. As seen in this figure, it is only necessary then to raise the bent strip from the lower part of the form block and then to slide it upwardly in order to remove the strips from the block. It will be understood that the ends of the finished frame may then be welded to form an integral structure.

It will be apparent that by changing the form block which usually will be bolted to the top, and by changing the wiper blocks so as to have blocks of different contour, frame members of different sections may be bent and that by using different tops provided with varying channel-ways and form blocks, numerous shapes may be bent, still in accordance with the invention.

Although only one form of the invention has been described in detail, it will be apparent to those skilled in the art that various modifications may be made without departing from the scope of the invention claimed.

What is claimed is:

1. A machine for bending a metal strip comprising a support, a rotary form block on the support and about the periphery of which the metal strip is to be bent and which has an annular guideway, means for clamping one end of the strip to the block at one point on the periphery of the block, a slide on the support, means on the support for directing the movement of the slide so that it may move inwardly and outwardly relative to the periphery of the form block, means on the slide engaging said guideway to effect movement of the slide inwardly and outwardly in accordance with the movement of said guideway, wiper means movably carried by the slide for pressing the strip against the periphery of the block as the latter rotates, and resilient means for moving the wiper means relative to the slide and towards the periphery of the block, said guideway being of such character that the wiper means is operatively held away from the periphery of the block along a predetermined portion of the latter adjacent the clamping means.

2. A machine for bending a metal strip comprising a support, a rotary form block on the support and about the periphery of which the metal strip is to be bent and which has an annular guideway, means for clamping one end of the strip to the block at one point on the periphery

of the block, a slide on the support, means on the support for directing the movement of the slide so that it may move inwardly and outwardly relative to the periphery of the form block, means on the slide engaging said guideway to effect movement of the slide inwardly and outwardly in accordance with the movement of said guideway, wiper means slidably carried by the slide for pressing the strip against the periphery of the block as the latter rotates, and resilient means for moving the wiper means relative to the slide and towards the periphery of the block, said guideway being of such character that the wiper means is operatively held away from the periphery of the block along a predetermined portion of the latter adjacent the clamping means.

3. A machine for bending a metal strip comprising a support, a rotary form block on the support and about the periphery of which the metal strip is to be bent and which has an annular guideway, means for clamping one end of the strip to the block at one point on the periphery of the block, a slide on the support, means on the support for directing the movement of the slide so that it may move inwardly and outwardly relative to the periphery of the form block, a plate pivotally mounted on the slide for pivotal movement about an axis parallel to the axis of rotary movement of the block, means on the plate engaging the guideway to effect movement of the slide inwardly and outwardly in accordance with the movement of said guideway, wiper means slidably mounted on the plate for pressing the strip against the periphery of the block, and resilient means for moving the wiper means relative to the slide and towards the periphery of the block.

4. A machine for bending a metal strip comprising a support, a rotary form block on the support and about the periphery of which the metal strip is to be bent and which has an annular guideway, means for clamping one end of the strip to the block at one point on the periphery of the block, a slide on the support, means on the support for directing the movement of the slide so that it may move inwardly and outwardly relative to the periphery of the form block, a plate pivotally mounted on the slide for pivotal movement about an axis parallel to the axis of rotary movement of the block, a pair of turnable elements on the plate engaging said guideway on opposite sides of the pivotal axis of the plate, and wiper means carried by the plate separately of the turnable elements for pressing the strip against the periphery of the block.

5. A machine for bending a metal strip comprising a support, a rotary form block on the support and about the periphery of which the metal strip is to be bent and which has an annular guideway, means for clamping one end of the strip to the block at one point on the periphery of the block, a slide on the support, means on the support for directing the movement of the slide so that it may move inwardly and outwardly relative to the periphery of the form block, a plate pivotally mounted on the slide for pivotal movement about an axis parallel to the axis of rotary movement of the block, means on the plate and engaging said guideway for effecting movement of the plate and slide in accordance with the movement of the guideway, a second slide on the plate and movable towards and from the plate pivot, a wiper block on the second slide, and resilient means on the plate urging the second slide towards the plate pivot.

6. A machine for bending a metal strip comprising a support, a rotary form block on the support and about the periphery of which the metal strip is to be bent and which has an annular guideway, means for clamping one end of the strip to the block at one point on the periphery of the block, a slide on the support, means on the support for directing the movement of the slide so that it may move inwardly and outwardly relative to the periphery of the form block, a plate pivotally mounted on the slide for pivotal movement about an axis parallel to the axis of rotary movement of the block, means on the plate engaging the guideway for effecting inward and outward movement of the plate and slide in accordance with the movement of the guideway, a second slide on the plate and movable towards and away from the plate pivot, resilient means on the plate for urging the second slide towards the plate pivot, and a wiper block pivotally carried by the second slide for pressing the strip against the form block.

7. A machine for bending a metal strip comprising a support, a rotary form block on the support and about the periphery of which the metal strip is to be bent and which has an annular guideway, means for clamping one end of the strip to the block at one point on the periphery of the block, a slide on the support, means on the support for directing the movement of the slide so that it may move inwardly and outwardly relative to the periphery of the form block, a plate pivotally mounted on the slide for pivotal movement about an axis parallel to the axis of rotary movement of the block, means on the plate engaging said guideway for effecting inward and outward movement of the plate and slide in accordance with the movement of the guideway, a second slide on the plate and movable towards and from the pivotal axis of the plate, resilient means urging the second slide towards said plate axis, a wiper block supporting member pivotally mounted on the second slide for pivotal movement about an axis parallel to the other axes, and a wiper block carried by said supporting member.

8. A machine for bending a metal strip comprising a support, a rotary form block on the support and about the periphery of which the metal strip is to be bent and which has an annular guideway, means for clamping one end of the strip to the block at one point on the periphery of the block, a slide on the support, means on the support for directing the movement of the slide so that it may move inwardly and outwardly relative to the periphery of the form block, a plate pivotally mounted on the slide for pivotal movement about an axis parallel to the axis of rotary movement of the form block, a pair of rollers on the plate having their axes disposed parallel to the plate pivot and being located at opposite sides of such plate pivot, said rollers engaging said guideway so that inward and outward movement of the plate and slide is effected in accordance with the movement of the guideway, a second slide carried by the plate for movement towards and from the plate pivot, resilient means urging the second slide towards such plate pivot, a wiper block supporting member pivoted on the second slide on a pivotal axis parallel to the other axes, and a wiper block pivotally carried by the supporting member for pivotal movement about another axis parallel to the others.

9. A machine for bending a metal strip comprising a support, a rotary form block on the

support and about the periphery of which the metal strip is to be bent and which has an annular guideway, means for clamping one end of the strip to the block at one point on the periphery of the block, a slide on the support, means on the support for directing the movement of the slide so that it may move inwardly and outwardly relative to the periphery of the form block, a plate pivotally mounted on the slide for pivotal movement about an axis parallel to the axis of rotary movement of the form block, a pair of rollers on the plate having their axes disposed parallel to the plate pivot and being located at opposite sides of such plate pivot, said rollers engaging said guideway so that inward and outward movement of the plate and slide is effected in accordance with the movement of the guideway, a second slide carried by the plate for movement towards and from the plate pivot, resilient means urging the second slide towards such plate pivot, a wiper block supporting member pivoted on the second slide on a pivotal axis parallel to the other axes, and a pair of wiper blocks pivotally carried by the supporting member for pivotal movement about spaced axes parallel to the other axes.

10. A machine for bending a metal strip comprising a support, a rotary form block on the support and about the periphery of which the metal strip is to be bent and which has an annular guideway, means for clamping one end of the strip to the block at one point on the periphery of the block, a slide on the support, means on the support for directing the movement of the slide so that it may move inwardly and outwardly relative to the periphery of the form block, a plate pivotally mounted on the slide for pivotal movement about an axis parallel to the axis of rotary movement of the form block, a pair of rollers on the plate having their axes disposed parallel to the plate pivot and being located at opposite sides of such plate pivot, said rollers engaging said guideway so that inward and outward movement of the plate and slide is effected in accordance with the movement of the guideway, a second slide carried by the plate for movement towards and from the plate pivot, resilient means urging the second slide towards such plate pivot, a wiper block supporting member pivoted on the second slide on a pivotal axis parallel to the other axes, a pair of wiper block carrying elements pivoted on the supporting member for pivotal movement respectively about spaced axes parallel to the others, and a wiper block slidably and resiliently mounted on each element.

11. A machine for bending a metal strip comprising a support, a rotary form block on the support and about the periphery of which the metal strip is to be bent and which has an annular guideway, means for clamping one end of the strip to the block at one point on the periphery of the block, a slide on the support, means on the support for directing the movement of the slide so that it may move inwardly and outwardly relative to the periphery of the form block, a plate pivotally mounted on the slide for pivotal movement about an axis parallel to the axis of rotary movement of the form block, a pair of rollers on the plate having their axes disposed parallel to the plate pivot and being located at opposite sides of such plate pivot, said rollers engaging said guideway so that inward and outward movement of the plate and slide is effected in accordance with the movement of the guideway, a second slide carried by the plate for movement

5 towards and from the plate pivot, resilient means urging the second slide towards such plate pivot, a wiper block supporting member pivoted on the second slide on a pivotal axis parallel to the other axes, a pair of wiper block carrying elements pivoted on the supporting member for pivotal movement respectively about spaced axes parallel to the others, and a wiper block slidably and resiliently mounted on each element, said wiper block being slidable on surfaces angled to said axes so that they may slidably move not only to and from the periphery of the form block but also longitudinally of the axis of the form block.

12. In a bending machine for bending a metal strip having angularly related portions, a form block on the support about the periphery of which the strip is to be bent and having a first surface generally in the plane of the block and a second surface upstanding to such plane so as to substantially fit the strip, a wiper block carrying element on the support and having a surface inclined to the plane of the form block, a wiper block on said element having an inclined surface fitting the inclined surface on the element and also having a first surface substantially parallel to the first surface of the form block and a second surface substantially parallel to the second surface on the wiper block, means retaining the element and wiper block assembled while allowing their relative movement along said inclined surfaces, means for urging the element towards the periphery of the form block, and means for effecting relative movement of the blocks along the periphery of the form block, the arrangement being such that when the wiper block is moved against the periphery of the form block with a strip in position on the latter the second surfaces on the blocks press against one angular or flange portion of the strip therebetween with the pressure then causing the wiper block to move along the inclined surface plane until the first surfaces on the blocks press the other angular or flange part of the strip therebetween.

13. In a bending machine for bending a metal strip having angularly related portions, a form block on the support about the periphery of which the strip is to be bent and having a first surface generally in the plane of the block and a second surface upstanding to such plane so as to substantially fit the strip, a wiper block carrying element on the support and having a surface inclined to the plane of the form block, a wiper block on said element having an inclined surface fitting the inclined surface on the element and also having a first surface substantially parallel to the first surface of the form block and a second surface substantially parallel to the second surface on the wiper block, means retaining the element and wiper block assembled while allowing their relative movement along said inclined surfaces, relatively light pressure resilient means urging the element and wiper block apart, relatively strong resilient means urging the element towards the form block, and means for effecting relative movement of the blocks along the periphery of the form block, the arrangement being such that when the wiper block is moved against the periphery of the form block with a strip in position on the latter, the second surfaces on the blocks to press one angular or flange of the strip therebetween with the pressure then causing the wiper block to move along the inclined surface plane until the first surfaces on the blocks press the other angular or flange part of the strip therebetween.

14. In a bending machine, a support, a form block on the support about the periphery of which a metal strip is to be bent, a wiper block carrying element on the support and having a surface inclined to the plane of the form block, a wiper block on said element having an inclined surface fitting the inclined surface on the element and also having a surface substantially parallel to said plane and adapted to press a part of the strip against a like parallel surface on the form block when the block moves along said inclined surfaces, means for moving the carrying element in a direction substantially parallel to said plane and towards the periphery of the form block, means on the wiper block engageable with the form block for effecting movement of the wiper block along said inclined surfaces when the carrying element is moved towards the form block whereby said part of the strip is pressed against the form block, and means for effecting relative movement of the form block and carrying element along the periphery of the form block.

15. In a bending machine, a support, a form block on the support about the periphery of which a metal strip is to be bent, a wiper block carrying member mounted on the support for movement towards and from the form block, a wiper block, means movably mounting the wiper block on the member for movement transversely to the plane of the form block, said wiper and form blocks having surfaces substantially parallel to said plane and between which a part of the strip is pressed when the wiper block is moved in said transverse direction, means on the wiper block engageable with the form block and cooperable with the first means for effecting movement of the wiper block in said transverse direction when the carrying member is moved towards the form block, so as to effect pressing of the strip between said surfaces, and means for effecting relative movement of the form block and carrying member along the periphery of the form block.

16. A machine for bending a strip of angular character, comprising a form block about the periphery of which the strip is to be bent and which has a first surface in its own plane and a second surface transverse to said plane for engagement respectively with the angular parts of the strip, a wiper means having similarly related first and second surfaces for pressing the angular parts of the strip against the corresponding surfaces on the block, means for moving the wiper means in a direction towards the form block and in the plane thereof to press a part of the strip between the first surfaces, means depending upon engagement of the first surface on the wiper means with said part of the strip for so moving the wiper means that the second surface of the wiper means is moved into engagement with the other part of the strip, and means for effecting relative movement of the wiper means and form block along the periphery of the latter.

17. A machine for bending a metal strip comprising a support, a rotary form block on the support and about the periphery of which the metal strip is to be bent and which has an annular guideway, means for clamping one end of the strip to the block at one point on the periphery of the block, a member movably mounted on the support for movement inwardly and outwardly relative to the periphery of the form block, an element on the member engaging the guideway to effect movement of the member inwardly and outwardly in accordance with the movement of the guideway, wiper means movably carried by said member for pressing the strip against the periphery of the form block as the latter rotates, and resilient means for moving the wiper means relative to said member and towards the periphery of the block, said guideway being of such character that the wiper means is operatively held away from the periphery of the block along a predetermined portion of the latter adjacent the clamping means.

18. A machine for bending a metal strip comprising a support, a rotary form block on the support and about the periphery of which the metal strip is to be bent and which has an annular guideway, means for clamping one end of the strip to the block at one point on the periphery of the block, a member movably mounted on the support for movement inwardly and outwardly relative to the periphery of the form block, an element on the member engaging the guideway to effect movement of the member inwardly and outwardly in accordance with the movement of the guideway, wiper means slidably carried by said member for pressing the strip against the periphery of the form as the latter rotates, and resilient means for moving the wiper means relative to said member and towards the periphery of the block, said guideway being of such character that the wiper means is operatively held away from the periphery of the block along a predetermined portion of the latter adjacent the clamping means.

19. A machine for bending a metal strip comprising a support, a rotary form block on the support and about the periphery of which the metal strip is to be bent and which has an annular guideway, means for clamping one end of the strip to the block at one point on the periphery of the block, a member movably mounted on the support and having means engaging the guideway so that the member may move inwardly and outwardly in accordance with the movement of the guideway, a plate pivotally mounted on the member for pivotal movement about an axis parallel to the axis of rotary movement of the block, wiper means slidably mounted on the plate, and resilient means for moving the wiper means relative to the member and towards the periphery of the block.

WILLIAM J. HALL.
